Lumber Wagon.

No. 13,503.

Patented Aug. 28, 1855.

UNITED STATES PATENT OFFICE.

JAS. PARSONS, OF DUBLIN, INDIANA.

WAGON.

Specification of Letters Patent No. 13,503, dated August 28, 1855.

To all whom it may concern:

Be it known that I, JAMES PARSONS, of Dublin, in the county of Wayne and State of Indiana, have invented a new and useful Improvement on Wagons; and I do hereby declare that the following is a full, clear, and exact description of the construction and operation of the same, reference being had to the annexed drawings, making a part 10 of this specification, in which—

Figure 1 is a perspective view, and Fig. 2 an end view.

A A represent in Fig. 1 the side pieces or ways resting upon the elevating blocks n n near the outer end of bolster C; F F, the cast arch and wrought axletree combined; see Fig. 2; H H, supporting braces with oblong bands e e; D D D D, elevating blocks upon the side pieces or ways; f f, notches in 20 the hind elevating blocks D D for the brace bands e e to drop into; c c, notches on the underside of hind blocks for the arch to rise into; s s, ears on opposite side of hind blocks to regulate their lateral motion; i i i i, adjusting or toggle pins to hind blocks; G G, ratchet wheels; L L, the shafts of ratchet wheels for winding and unwinding chains, see Fig. 2, in loading and unloading; K, the bar or lever to apply in winding, &c.

30 The nature of my invention consists in the peculiar adaptation of my wagon in its changeable character in the wide position of the side pieces or ways, and the sliding manner in which they pass through the brace bands e e and the open mortises or slots o o in the castings of the arch; also in the open mortises or slots o o of the arch, and in the form and uses of the oblong brace bands e e in holding in their proper place and giving 40 the sliding motion to the hind elevating blocks D D; also in the peculiar adaptation of the hind elevating blocks D D in the coupling operation, thereby rendering it extremely convenient, for long or short work 45 in loading and unloading and hauling, every variety of loading and hauling which such wagons are capable of performing.

I am aware however that arches, singly and combined, and ways or couplings, also 50 braces and elevating blocks resembling mine but differently arranged have been used in wagons, for similar purposes, but still, such

resemblance without the width and the sliding principle as in mine form no part of my invention, but it is in their peculiar application as hereinafter substantially set forth and described or their equivalents either in form or material.

Having thus described the nature and operation of my invention, what I claim as new, and desire to secure by Letters Patent, is,

1. I claim the arrangement of the side pieces or ways A A resting upon the elevating blocks n n near the outer end of 65 bolster C, thereby gaining a greater width between them than is obtained in other wagons constructed for similar purposes, thus giving space for loading if raised on a plank or platform, to raise partly above 70 and between them if necessary to clear the ground in hauling, also the manner of their forming the connection between the forward and hind wheels, by passing or sliding through the brace bands e e and the mortises 75 or slots o o of the arch as hereinafter described.

2. I claim in the structure of cast arch with the open mortises, or slots o o and their uses, that when the arch F F and wrought axletree combined as represented in Fig. 2 when supported by the hind wheels, the mortises or slots o o will be brought nearly or quite in a horizontal position for the reception of the side pieces or ways as before described, 85 thus serving the purposes of coupling the wagon long or short, to suit circumstances.

3. I claim the peculiar adaptation of the oblong bands e e of the braces H H through which the side pieces or ways slide and the 90 hind elevating blocks D D pass, and the blocks being held in their proper position by the bands e e dropping into the notches f f of elevating blocks D D, thus giving them the sliding motion upon, the side 95 pieces or ways, and the side pieces or ways are permitted to slide freely through them and under the blocks; and from thence they form a connection with the cast arch and wrought axletree by a stirrup firmly binding them together.

4. I also claim the manner of so arranging the hind elevating blocks D D as to give them the sliding principle as previously de-

scribed, and the ears *s s* on opposite sides, thus rendering them adjustable in coupling the wagon long or short, by means of the steady or toggle pins *iii i*, and again by their holding in connection with the braces, the arch, in a perpendicular position, by the upper part of the casting of mortises or slots

o o being notched into the elevating blocks, as at *c c* described and shown.

JAMES PARSONS.
